(57) **CLAIM**

The ornamental design for an electrical connector, as shown and described.

DESCRIPTION

FIG. 1 is a front view of an electrical connector showing my new design;

FIG. 2 is a bottom view thereof;

FIG. 3 is a back view thereof;

FIG. 4 is a left side view thereof;

FIG. 5 is a right side view thereof;

FIG. 6 is a top view thereof; and,

FIG. 7 is a perspective view thereof.

The broken lines shown in FIG. 2 are for the purpose of illustrating portions of the electrical connector and form no part of the claimed design.
